ATTORNEY

UNITED STATES PATENT OFFICE.

NELSON H. BRAY, OF SAN FRANCISCO, CALIFORNIA.

AUTOMATIC IGNITER FOR ORCHARD-HEATERS.

1,328,788.

Specification of Letters Patent. Patented Jan. 20, 1920.

Application filed March 4, 1918. Serial No. 220,150.

To all whom it may concern:

Be it known that I, NELSON H. BRAY, a citizen of the United States, and a resident of the city and county of San Francisco, State of California, have made a new and useful Invention—to wit, Automatic Igniters for Orchard-Heaters; and I do hereby declare the following to be a full, clear, concise, and exact description of the same.

10 The invention relates particularly to and has for its object means for automatically igniting orchard heaters by a drop in temperature to the danger point indicating frost.

15 Another object is to provide means whereby all of the orchard heaters within the danger zone will be simultaneously ignited, saving valuable time at a critical period.

This invention operates on the principle 20 of utilizing a confined body of air which will contract with a drop in temperature, forming a partial vacuum which is utilized to siphon a quantity of acid into contact with an ignitable mixture adapted to propagate a flame, which will ignite the oil or 25 other fuel within the orchard heaters.

In this specification and the annexed drawings the invention is illustrated in the form considered to be the best, but it is to be 30 understood that the invention is not limited to such form because it may be embodied in other forms, and it is also to be understood that in and by the claims following the description it is desired to cover the invention 35 in whatever form it may be embodied.

In the accompanying one sheet of drawings:

Figure 1 is a diagrammatic illustration in 40 elevation of an orchard heater having an igniter applied thereto in accordance with this invention.

Fig. 2 is an enlarged elevation of an igniter constructed in accordance with this invention shown partially in cross section.

45 Fig. 3 is a cross section of the same, taken on the line III—III, Fig. 2.

In detail the construction illustrated in the drawings includes the acid chamber 1, preferably composed of a glass test tube, 50 containing a quantity of sulfuric acid 2. The open end of the tube is closed by the stopper 3 preferably of rubber, provided with a groove as at 4 to form a vent admitting atmospheric pressure to the acid tube 1.

55 The air chamber 5 is preferably a glass test

tube, similar to the tube 1 but of greater capacity, inverted and forced over the extension 6 of the stopper or plug 3. This plug has a central longitudinal opening to receive the glass tube 7, having its lower end immersed in the acid 2 and extending through the plug, above the level of which it terminates within the chamber 5. The plug hermetically engages the outer surface of the tube 7 and the opening of the tube 5, whereby the chamber within the tube 5 is hermetically sealed from the atmosphere, except through the acid chamber 1. Within the chamber 5 resting upon the plug 6 adjacent to the upper end of the tube 7 is an annular 60 tablet 8 composed of a material adapted to be ignited by sulfuric or other acid. For this purpose I prefer to use what is commercially known as Greek fire, composed of chlorate of potash and brown sugar, with 65 various modifications.

The cover X of the heater is provided with an opening to receive the ignition device, leaving a portion of the chamber 5 exposed. For this purpose I provide the chamber 5 80 with a flange or ring 9 preferably of rubber, to engage the edges of the hole in the cover X, to suspend the device with the combustible element within the heater.

The invention operates substantially as 85 follows: The orchard heaters are distributed through the orchard or other area to be protected in the usual manner, and are preferably filled with crude oil or other fuel, such as X¹. The cover X is placed in position 90 and the ignition device inserted within the cover, preferably suspended above the fuel.

A drop in temperature brings about a proportionate contraction of the volume of air 95 within the chamber 5, until a partial vacuum is formed therein at the dangerous temperature, say 40° Fahrenheit, at which time this partial vacuum will exert its suction through the tube 7 drawing the acid 2 therethrough and discharging it onto the combustible tablet 8, which is ignited thereby, giving off a large volume of combustible gases, the heat and pressure of which will explode the glass tube 5, at which time the liberated combustible gases will burst into flames igniting the 100 fuel X¹ within the heater. The ignition of the fuel within the heater causes a large volume of heat to be given off through the stack X² warming the zone threatened with 105 frost, in the usual manner.

By the use of this invention, only those orchard heaters which are within the immediately threatened zone of frost will be ignited, which accomplishes a great saving in fuel in large orchards where only a restricted area might be threatened. The other heaters will not be ignited until the dangerous drop in temperature spreads thereto. A still greater advantage is that all of the orchard heaters within the threatened area will be simultaneously ignited by this automatic means. Because of the great expense of operating orchard heaters, they are not ignited until the danger point is reached, which may be a matter of only a few degrees, and because of the labor incidental to igniting these heaters by torches or other means now in practice, it is impossible, without more help than is usually available, to ignite a sufficient number of heaters within the zone to raise the temperature above the frost point.

The tablet form of ignitable powder as at 8 is preferred for the reason that powdered or granulated substances would be liable to ignition by sifting into the acid through the tube 7, particularly in assembling the device for use. As the acid 2 passes out of the tube 1, air pressure through the vent 4 prevents the formation of a vacuum between the end 30 of plug 3 and the surface of the acid. In handling the device before it is inserted in the heater, the tube 1 is forced up onto the plug 3 to close the top of the vent 4 and prevent the spilling out of any of the acid 2. Just before inserting into the cover X the tube is partially withdrawn from the plug 3 to open the top of this vent 4. In the sealed condition it is impossible for any of the acid 2 to reach the chamber 5, should 40 the device be dropped or laid on its side, as the quantity of acid is proportioned to the size of the tube 1 so that the lower end of the tube 7 will be exposed if the device was inverted or laid on its side. Only a small 45 quantity of acid is necessary for the purpose, the quantity of acid in proportion to the volume of air, is the determining factor in regulating the degree of heat at which the two elements will be mingled.

Having thus described my invention, what I claim and desire to secure by Letters Patent is:

1. An igniter including a reservoir adapted to contain liquid; a sealed chamber adapted to contain an ignitable compound; and a tube submerged in said liquid and extending into said chamber adjacent to said compound.

2. An igniter including a reservoir con-

taining liquid; a sealed chamber containing 60 a compound ignitable by said liquid; a tube having one end sealed by said liquid and extending into said reservoir, whereby said liquid will be drawn into said chamber by volumetric contraction of the contents of 65 said chamber.

3. In combination with an orchard heater, an igniter including a reservoir adapted to contain liquid; a sealed chamber adapted to contain a compound ignitable by said liquid; a passage between said reservoir and said chamber; whereby said liquid will be drawn into said chamber by volumetric contraction of the contents of said chamber.

4. An igniter including separate containers, each to contain substances adapted to be co-mingled to produce combustion, and a connection between said containers through the medium of which said substances are mingled by the volumetric action of a content in one of said containers, said action being caused by variations in atmospheric temperature.

5. An igniter comprising a breakable container and a reservoir, each containing substances adapted to be co-mingled to produce combustion, and a thermally controlled passage between the container and reservoir through which the contents of the latter will be drawn into the container by volumetric contraction of the contents in the container to mingle said substances, whereupon the container is broken by the expansion and combustion of the co-mingled substances.

6. In combination with an orchard heater 95 an igniter insertible in a wall of the heater, said igniter including a breakable container having a flange intermediate its ends for supporting the igniter in the heater, a reservoir, said container and reservoir being 100 adapted to contain substances to be co-mingled to produce combustion, and a thermally controlled passage between the container and reservoir through which the contents of the latter will be drawn into the 105 container by volumetric contraction of the contents in the container to mingle said substances, whereupon the container is broken by the expansion and combustion of the co-mingled substances.

In testimony whereof, I have hereunto set my hand at San Francisco, California, this 25th day of Feb'y 1918.

NELSON H. BRAY.

In presence of—
LINCOLN V. JOHNSON,
A. J. HENRY.
